JACK SPRING HAVING SPACED LOOPS OF
DIFFERENT DIAMETERS

Andrew Mouw, Huntington Woods, Mich., assignor to No-Sag Spring Company, Warren Township, Mich., a corporation of Michigan

Application May 25, 1949, Serial No. 95,287

7 Claims. (Cl. 155—179)

1

This invention relates to jack springs for supporting the border wire above a frame and for applying an outward stress to the springs of the assembled cushion and to the assembled cushion and jack springs.

Difficulty has always been experienced in the art of constructing spring cushions in providing means for supporting the border wire above the frame and for stretching the spring assembly sidewardly toward the frame edges.

In constructing a spring cushion, a frame of wood or other relatively strong material has strips of zigzag springs stretched from the forward to the back edge thereof and secured in place by suitable clips. The spring strips are set on an arc of much smaller radius than the arc of the bolster which the strips assume when stretched across the frame. Wire clips interconnect the springs interjacent the ends across the seat and a border wire extends along the sides and front of the seat above the frame. Suitable means are provided (not herein illustrated) for supporting the border wire above the frame at the front edge of the seat cushion, and jack springs of the present invention are utilized for supporting the border wire above the frame at the side edges thereof. The jack springs are also useful in providing a tension to the spring assembly outwardly toward the side edges of the cushion.

In one form of the invention the jack spring embodies a wire loop of a diameter to permit the wire of the spring strip to be threaded therethrough. Arms extend outwardly from the loop at substantially right angles to each other, with one arm of greater length than the other. The ends of the arms are bent laterally and rearwardly to provide feet by which the spring is secured to the frame and to the border wire.

In another form of the invention, the longer arm and loop has the second arm extending downwardly and formed into second loop substantially the size of the first and further extended downwardly and formed into a large loop and extended outwardly to form the attaching arm having a foot thereon. The second small loop has a coil spring secured thereto for pulling the loop toward the outer edge of the frame, and the larger loop, being more resilient than the smaller loops, permits the jack spring and the supporting strip and border wire to deflect.

2

Accordingly, the main objects of the invention are: to provide a jack spring which is capable of being threaded on a spring strip for supporting a border wire against suitable deflection while applying an outward tension to the spring strip; to support the border wire at the side of the cushion and draw the spring assembly outwardly toward the cushion sides by jack springs having a loop through which the edge springs are threaded and which jack springs have feet by which the arms thereof are secured to the border wire and frame; to provide a multilooped jack spring with a large loop and with arms having feet which are attachable to a border wire and frame for applying an outward tension to a spring assembly when the outermost springs of which are threaded through one of the loops of the jack springs by a spring secured to the side portion of the frame and to a second loop, and, in general, to provide a spring structure having the side portion of the border wire resiliently supported above the frame and the spring assembly drawn outwardly toward the sides, which is simple in construction and economical of manufacture.

Other objects and features of novelty of the invention will be specifically pointed out or will become apparent when referring, for a better understanding of the invention, to the following description taken in conjunction with the accompanying drawings, wherein:

Fig. 1 is a broken plan view of a seat cushion having the border wire and the spring assembly stressed at the side edges by jack springs of the present invention;

Fig. 2 is an enlarged sectional view of the structure illustrated in Fig. 1, taken on the line 2—2 thereof;

Fig. 3 is an enlarged perspective view of the jack spring illustrated in Fig. 2;

Fig. 4 is a view of structure, similar to that illustrated in Fig. 1, showing a modified form thereof;

Fig. 5 is an enlarged sectional view of the structure illustrated in Fig. 4, taken on the line 5—5 thereof, and

Fig. 6 is a view in perspective of the jack spring illustrated in Fig. 5.

Referring to Figs. 1 and 4, a cushion 10 is illustrated, having a frame 11 comprising a front frame element 12, a rear frame element 13 and

side frame elements 14 which are connected together to form a rectangular frame member. A plurality of strips of zigzag springs 15 are secured across the front and rear frame elements 12 and 13 by suitable clips 16. The assembled spring strips are interconnected by wire clips laterally across the assembly. A border wire 18 is secured to the rear frame element 13 in a manner to extend above the side elements 14 and the front element 12 of the frame member 11. The border wire is secured against downward deflection at the front end by suitable spring means (not herein illustrated).

Referring to Figs. 2 and 3, a spring element 19 is illustrated as being employed for supporting the border wire 18 above the side frame element 14 while providing an outward force to the assembly of the spring strips 15. As illustrated more specifically in Fig. 3, the spring element 19 comprises a large loop 21 having an arm 22 extending therefrom which is bent laterally at 23 and rearwardly at 24 to provide an attaching foot therefor. The wire extends upwardly at 25 from the loop 21 and is formed into a small loop 26 from which it extends upwardly at 27 and again formed into a small loop 28. A second arm 29 extends substantially at right angles to the portion 27 and is bent at right angles at 31 and reversely bent at 32 to form an attaching foot on the end of the arm 29. The spring strips 15 at the side edges of the assembly are threaded through the upper loop 28 of the spring elements 19, after which the foot on the end of the arm 29 is attached to the border element 18 by a clamping band 33. The lower arm 22 of each spring element 19 has its foot clamped to the inner surface of the side elements 14 of the frame 11 by suitable clips 16. Straps 34 are secured to the outer face of the side frame elements 14 opposite each spring element 19, having an inwardly directed end 35 containing an aperture in which the end hook on a coil spring 36 is secured, the other end of the spring 36 being hooked into the central loop 26. The springs 36 provide an outward tension to the spring elements 19 which pivot in the clips 16 and produce an outward pull to the side edges of the spring and to the spring strips 15 thereof. This pull also applies an upward tension to the foot on the end of the arm 29 to thereby assist in resisting the downward deflection of the side portion of the border wire 18. The spring provides a double function of resisting the deflection of the side portion of the border wire and also to provide an outward tension to the spring assembly. The amount of tension provided may be regulated by the number of spring elements 19 employed and the strength of the springs 36 which are utilized therewith.

Referring to Figs. 5 and 6, a further form of the invention is illustrated, that wherein the side elements 37 of the border frame are of greater height than the front and rear border elements 12 and 13. A spring element 38 has a small loop 39 and arms 41 and 42 extend therefrom at substantially right angles to each other. The arm 42 is of shorter length than the arm 41, each arm being provided with a foot portion 43 similar to the foot portions on the spring element 19 of Fig. 3. The endmost springs 15 adjacent to the frame elements 37 are threaded through the loops 39 of the spring elements 38, and thereafter the spring elements 38 have the foot 43 on the arm 41 secured by a band 33 to the border wire 18. The short arm 42 is then

secured by a clip 16 to the side frame elements 37. When securing the arm 42 to the elements 37, the springs stretched between the front and rear border elements 12 and 13 are drawn toward the side elements 37 and tension is applied to the arm 41 which resists the deflection of the border wire 18. The springs 38 have the dual function of applying an outward tension to the spring strips 15 and applying an upward force to the border element 18 to resist its deflection.

What is claimed is:

1. A spring for supporting a border wire at the edge of a seat cushion against downward and inward deflection, comprising a spring wire formed into a large loop with one end portion extended to provide an arm having an attaching foot, with the other end portion extended and formed into two small spaced loops which are spaced from said large loop, and further extended to form a second arm having an attaching foot.
2. A spring for supporting a border wire at the edge of a cushion against downward and inward deflection, comprising a spring wire formed to provide two spaced adjacent loops and a large loop spaced therefrom, said loops being disposed in substantial alignment, the portions extending from the endmost loops forming arms having attaching feet formed on the ends.
3. A spring for supporting a border wire at the edge of a cushion against downward and inward deflection, comprising a spring wire formed to provide two spaced loops and a large loop spaced therefrom, said loops being disposed in substantial alignment, the portions extending from the endmost loops forming arms having attaching feet formed on the ends, said arms being in diverging relation from the loops outwardly relative to each other and said feet being formed on the same side of a plane through the loops.
4. A spring for supporting a border wire at the edge of a spring cushion, comprising a spring wire formed in U-shape providing a pair of arms extending from a web portion, the center of the web portion being formed into a small loop, one end of the junction of the web portion and one arm being formed into a similar small loop, the junction between the other end of the web portion and the other arm being formed into a large loop.
5. A spring for supporting a border wire at the edge of a spring cushion, comprising a spring wire formed in U-shape providing a pair of arms extending from a web portion, the center of the web portion being formed into a small loop, one end of the junction of the web portion and one arm being formed into a similar small loop, the junction between the other end of the web portion and the other arm being formed into a large loop, the ends of the arms being bent outwardly away from a plane through the arms to form attaching feet.
6. A spring for supporting a border wire at the edge of a spring cushion, comprising a spring wire formed in U-shape providing a pair of arms extending from a web portion, the center of the web portion being formed into a small loop, one end of the junction of the web portion and one arm being formed into a similar small loop, the junction between the other end of the web portion and the other arm being formed into a large loop, the ends of the arms being bent outwardly away from a plane through the arms to form attaching feet, said arms being in diverging relationship relative to the web portion.
7. In a spring assembly, a frame, a plurality of spring strips made of wire bent in zigzag form

stretched across the frame, a border wire surrounding said spring strips, and a spring having a first loop receiving the wire of the endmost spring strip and having an arm extending therefrom and attached to the border wire, said spring having a second loop to which a coil spring attached to the frame is secured, said spring having below said second loop a large loop from which an arm extends having an attaching foot which is secured to the frame whereby said spring provides resistance against downward deflection of the border wire and the inward movement of the endmost spring strip.
